[57] CLAIM

The ornamental design for a transmitter for use with a
3-D mouse, as shown and described.

DESCRIPTION

FIG. 1 is a descriptive view of a triangular-shaped
transmitter, for use with a 3-D mouse, according to the
present invention;

FIG. 2 is a left side elevational view of the transmitter
of FIG. 1, the right side being a mirror image;

FIG. 3 is a top plan view of the transmitter of FIG. 1;
FIG. 4 is a rear elevational view of the transmitter of
FIG. 1; and,

FIG. 5 is a bottom plan view of the transmitter of FIG.
1.

FIG. 1

FIG. 2

FIG. 3

FIG. 4

FIG. 5
